UNITED STATES PATENT OFFICE.

JAMES P. WILLIAMS, OF NEW YORK, N. Y.

SASH LOCKING AND PIVOTING DEVICE.

1,176,012.

Specification of Letters Patent. Patented Mar. 21, 1916.

Application filed August 10, 1914. Serial No. 856,040.

To all whom it may concern:

Be it known that I, JAMES P. WILLIAMS, citizen of the United States, residing at New York, in the county of New York and State 5 of New York, have invented certain new and useful Improvements in Sash Locking and Pivoting Devices; and I do declare the following to be a full, clear, and exact description of the invention, such as will 10 enable others skilled in the art to which it appertains to make and use the same.

This invention relates to improvements in sash locking and pivoting devices for windows.

15 The object of the invention is to provide a simple and efficient device of this character which provides for the raising and lowering of the sash, the swinging or reversal thereof and the easy removal of the sash from the 20 frame.

With this and other objects in view, the invention consists of certain novel features of construction and the combination and arrangement of parts as will be more fully 25 described and claimed.

In the accompanying drawings; Figure 1 represents a front elevation of a window equipped with this invention and with parts broken out and the connecting means for 30 the sash and frame shown in operative position; Fig. 2 is a similar view with the sash and frame connecting means in operative position and with the pivoting elements shown in position for use; Fig. 3 is a vertical section taken on the line 3—3 of Fig. 2; Fig. 4 is an enlarged vertical section showing the sash guiding means in operative position and with the pivoting elements in inoperative position; Fig. 5 is a similar view 35 showing the sash connecting and guiding means in inoperative position and the pivoting means in operative position. Fig. 6 is a transverse section taken on the line 6—6 of Fig. 1; Fig. 7 is a similar view taken on the 40 line 7—7 of Fig. 2; Fig. 8 is a front elevation of the inner face of the window frame with parts broken out and in section on the line 8—8 of Fig. 4; Fig. 9 is an edge view of a portion of the window sash showing 45 one of the connecting rollers.

It is well known that many accidents occur by persons washing windows which are not reversible and which necessitate the operator sitting on the sill and this is especially true in high buildings, many deaths 50 having occurred by reason of the falling of

the window washers from the upper floors of such buildings, and it is to avoid these accidents that this invention is especially designed.

In the embodiment illustrated a window frame 1 is shown having the usual stiles 2 and sill 2'. On the inner face of each of the stiles 2 are secured two laterally spaced sash guides 3 and 4 which extend from the top 60 to the bottom of the stiles and on which the sashes are adapted to slide in a manner to be described whereby the sash is held in position and the usual beads thus dispensed with. These guides 3 and 4 are preferably 65 made of angle iron with one flange thereof projecting laterally and disposed edgewise to engage with coöperating means carried by the sash. Each sash 5 is provided on one of its side edges with a plurality of longitudinally spaced grooved blocks 6 designed to slidably engage the laterally projecting flange of one of the guides 3 or 4 as the case may be. The other side edge of the sash 5 is provided with longitudinally spaced inwardly extending recesses or pockets 7 or 8 70 with a solid portion 9 arranged between them and which latter has an aperture 10 extending from edge to edge thereof, the outer end of said aperture being reduced as 75 shown at 11 and the inner portion enlarged as shown at 12 for a purpose to be described. The outer edge of this block 9 is cut away a sufficient distance to form a seat 80 and to house a spring metal strap 13 which 85 is fixed intermediately of its ends to said block 9 with its free ends equipped with peripherally grooved rollers 14 which are revolvably mounted on said ends. These rollers 14 are positioned opposite the pockets 90 7 and 8 and are designed to be housed therein when desirable and for a purpose to be described. These peripherally grooved rollers 14 are designed to normally engage and 95 travel on the laterally projecting flanges of 100 the sash guides 3 and 4 on the adjacent side of the frame 1 and are normally held yieldably in engagement with said flanges by the resiliency of said strap 13.

The roller retracting means here shown is 105 clearly shown and described in detail in my copending application Serial No. 856,039 filed August 10, 1914 and hence will only be referred to generally herein. Each roller is provided with retracting means in the 110 form of an eye bolt 15 connected with a link 16 which extends through an aperture 17

in the rear wall of the pocket and in which said roller is to be withdrawn and the outer end of this link 16 is connected with a bell crank or cam lever 18 operable when turned 5 in one direction to retract the roller connected therewith and house it within the pocket opposite which it is disposed and when this lever is turned in the other direction it releases said link and permits the roller to be 10 projected by the spring strap 13 into frictional engagement with the lateral flange of the sash guide. These levers 18 are fulcrumed in suitable brackets 19 mounted on the inner edge of the side member of the 15 sash 5. The flanges of the guide members 3 and 4 which are secured to the inner faces of the stile at one side of the frame are preferably provided with a plurality of longitudinally spaced apertures 3' and 4' respectively which are designed to receive the free 20 end of the pivot member now to be described. As shown this pivot member comprises an angular shank 20 which extends through the aperture 10 in the block 9 25 through the reduced outer portion 11 thereof and through an aperture 11' in strap 13 which latter is also made angular in cross section to receive said shank and hold it against turning for a purpose to be described. 30 The end of the shank which passes through the angular aperture 11' is preferably pointed to facilitate its engagement with one of the apertures in the flange of the sash guide and the other end thereof being provided 35 with a cylindrical head which projects through the side member of the sash and is coarsely threaded to receive an adjusting nut 21 the turning of which on said screw threaded head retracts or projects it in a 40 manner to be described. This nut 21 is elongated to provide a bore or socket therein of sufficient length to receive the threaded end of the shank 20 and provide for its projection or retraction to a predetermined extent. 45 This nut 21 is provided at its inner end with an annular groove 22 to receive a supporting member 23 and whereby said nut is swiveled in connection with said plate. As shown the inner end of this nut fits within the 50 enlarged portion 12 of the aperture 10 and the outer face of the block 9 around said aperture is recessed to form a seat for said member 23 which is secured to the block by screws or other suitable fastening elements and by 55 means of which the nut is supported on the sash. As shown this nut supporting member is composed of two plates, an integral plate 24, and a plate composed of sections 25 and 26. The outer plate 24 has an aperture therein of a size to fit within the groove 22 of the nut and is provided with a slot 24' leading therefrom to adapt the nut to be inserted. The inner plate is formed of the 60 two sections 25 and 26 which are provided on their abutting edges with registering notches 65

27 which are adapted to register and form an aperture the walls of which fit in the grooves 22 of the nut and these two sections are secured together by riveting or in any other suitable manner. The member 23 is 70 constructed as above described to facilitate the assembling of the nut and afford a strong support therefor.

From the above description it will be obvious that when the nut 21 is turned in one 75 direction the shank 20 will be retracted into the socket therein and its pointed end withdrawn from engagement with the aperture in the guide flange as shown in Fig. 4 while when said nut is turned in the opposite direction said shank will be projected through the edge of the sash and into engagement with the flange of the sash guide. While apertures are shown formed in the flanges of the sash guides for the reception of the 80 ends of the shank of the pivot member it is obvious that it is not necessary that these shanks be inserted in one of the apertures as it may be held in frictional engagement with the flange but the apertures are provided 85 to render the holding of the sash in operative position more reliable. Two of these pivoting devices are provided for each sash as is shown clearly in Figs. 1 to 3 and are 90 preferably disposed at points midway the 95 length of the sash in the side members thereof and at points diametrically opposite so that when said devices are in operative position the sash may be readily swung on said pivot members to reverse it for cleaning the 100 outer faces of the panes.

The usual sash retaining beads 28 are 105 preferably employed on the stiles of the frame at the inner and outer edges of the sash guide ways and are hinged to open outwardly into the position shown in Fig. 7 to provide for the removal or swinging of the sash when desired.

In the operation of this device when it is 110 desired to reverse the position of the sash for cleaning or other purposes the levers 18 are first swung inward toward each other into the position shown in Fig. 2 for retracting the rollers with which they are connected and thereby freeing the sash at this 115 side of the window from the guides. The pivoting device 21 at the right hand side of the sash is then turned so as to force the shank thereof into engagement with the sash guide on the adjacent side of the frame and 120 a continued turning of the nut in said device will cause the sash to move bodily toward the left a sufficient distance to disengage the grooved blocks 6 thereof from the laterally projecting flanges of the guides 125 3 or 4 as the case may be. The other pivoting device at the left side of the sash is then turned to move its shank outward into engagement with the guide on the adjacent 130 side of the window frame the rollers having 135

been already withdrawn from said guides to provide sufficient space for the sash to move laterally a sufficient distance to disengage the blocks 6 from the guides at the right of the window and also to cause the side member of the sash that carries the rollers to swing clear of the guides on the adjacent side of the window frame. When these pivoting devices have been so disposed the beads 28 are swung outwardly and the sash may then be swung on its pivot members into the position shown in dotted lines in Fig. 3 or they may be entirely reversed if desired and thus the window may be washed on both sides from the interior of the building without endangering the life of the operator. When it is desired to remove the sash these pivot members are turned to retract the shanks thereof within their nuts a sufficient distance to clear the flanges of the guide members and the sash may be easily lifted out.

To return the sash to operative sliding position it is first placed within the frame and the bead 28 swung inward to hold it against lateral movement while the guide members thereof are being adjusted. The blocks 6 are first engaged with the flanges of the guide members on the adjacent side of the window frame and the levers 18 are turned outwardly into the position shown in Fig. 1 whereby the rollers 14 are projected by the spring 13 into frictional engagement with the flanges of the guides of the adjacent side

of the window frame and the sash is then 35 ready to be moved up or down in the usual manner.

From the above description it will be obvious that this improved device may be readily disposed into either operative or inoperative position by the simple turning of the nut thereof in one direction or the other.

I claim as my invention:—

The combination with a window-frame having stiles provided with guides, of a 45 window-sash provided on one of its side edges with grooved blocks to slidably engage the guide on one stile, the other side edge of said sash being provided with retractable guide engaging elements, said 50 frame being wider than the sash, and projectable and retractable pivoting devices carried by opposite side rails of said sash and engaging said guides, whereby the sash may be moved bodily when said retractable 55 flange engaging elements are in retracted position by forcibly engaging the pivoting device at the other side of the sash with its guide to cause said sash to clear said guide and permitting it to be swung or removed 60 from the frame.

In testimony whereof I have hereunto set my hand in presence of two subscribing witnesses.

JAMES P. WILLIAMS.
